Primary Examiner—A. Hugo Word*Assistant Examiner*—Doris V. Coles*Attorney, Agent, or Firm*—Lewis Anten; Amedeo Ferraro[57] **CLAIM**

The ornamental design for a combined key holder and self-defense weapon, as shown and described.

DESCRIPTION

FIG. 1 is a front, right side perspective view of a combined key holder and self-defense weapon, showing my new design;

FIG. 2 is a rear elevational view thereof;

FIG. 3 is a bottom plan view thereof;

FIG. 4 is a top plan view thereof;

FIG. 5 is a right side elevational view thereof;

FIG. 6 is a left side elevational view thereof;
FIG. 7 is a rear elevational view of a second embodiment, being like the embodiment shown in FIGS. 1-6 in all respects except the top portion; and,

FIG. 8 is a top plan view thereof.

The broken line showing of a key ring in FIG. 1 is for illustrative purposes only and forms no part of the claimed design.

FIG. 1

FIG. 2

FIG. 3

FIG. 4

FIG. 5
